FLEXIBLE GAS SEAL FOR A BLAST FURNACE

Walter C. Wilkening, Chicago, Ill., assignor to John Mohr & Sons, Chicago, Ill., a corporation of Illinois

Filed Dec. 12, 1958, Ser. No. 779,894

8 Claims. (Cl. 214—36)

My invention relates to an improved gas seal for the rotatable bell hopper of a blast furnace.

In a blast furnace, the furnace materials (ore, limestone, and coke) are dumped by the skip car into the small or upper bell hopper. This hopper is a cylindrical sleeve with a beveled lower margin. A conical bell or valve is normally held upwardly against this hopper and accordingly holds the charged materials in the hopper. Periodically, the bell is moved downwardly to cause the charging materials to discharge downwardly into the large bell hopper. This bell hopper is similarly closed by a vertically movable conical bell or valve which is normally held in seated position against the lower beveled margin of the hopper. In some furnaces a third similarly constructed bell hopper and bell is provided and is likewise intermittently filled with the charging materials and intermittently discharged.

In order to distribute the charge of materials in circumferentially uniform fashion, it is customary to provide at least one bell hopper, preferably the small bell hopper, with means to rotate the same by a predetermined angle between successive actuations. After successive loads that hopper is rotated bodily in a program of differing angular rotations and at the end of each such rotation the bell is depressed and the load discharged. Thus the loads are distributed at spaced points about the furnace to provide circumferentially uniform load distribution.

In this revolving distributor construction it is necessary to provide a gas-tight seal between the revolvable bell hopper and the jacket of the furnace. Otherwise the valuable and dangerous blast furnace gases will escape and the whole purpose of the bell hoppers defeated. The seal required for this purpose must withstand the adverse conditions of dust, heat, and other conditions incident to blast furnace operation. It must also have long life and be readily installed and removed.

In accordance with the present invention the revolving distributor mechanism has a bell hopper seal defined by a pair of fixed rings which coact to define an annular space facing and surrounding the cylindrical outer face of the bell hopper. These rings may be disassembled to provide access from the top of the annular space. The seal ring proper is of silicone compound having an outer section that fits snugly in the radially outward portion of the annular space formed by the rings, an inwardly extending supporting portion which nests against the upper of the rings, and a downwardly and inwardly extending flexible lip portion which likewise seats against the upper of the rings and projects radially inwardly therefrom to a seating engagement with the cylindrical wall of the bell hopper. A spring encircles the flexible lip portion of the seal and fits in the space defined by the supporting portion and the flexible lip portion. This spring pushes the lip portion radially inwardly against the cylindrical outer surface of the hopper to provide the gas tight seal. The pressure created from the hot blast gas also serves to

2

urge the flexible lip into tighter engagement with the bell hopper.

It is therefore a general object of the present invention to provide an improved flexible gas seal for the revolving distributor of a blast furnace.

It is a further object of the present invention to provide an improved flexible gas seal for the revolving distributor of a blast furnace having a flexible lip portion that is encircled by a spring to define a tight seal even in the absence of gas pressure.

It is another object of the present invention to provide an improved seal for the revolving distributor of a blast furnace which utilizes a ring having a flexible sealing lip which is urged by the gas pressure to increased sealing relation with the hopper.

Further it is an object of the present invention to provide an improved gas seal for the revolving distributor of a blast furnace which utilizes a pair of rigid fixed rings which encircle the bell hopper and define an annular space with a beveled inner upper wall in conjunction with a fixed seal ring having an outer portion that fits snugly against the outer portions of the space so defined, has a support portion extending radially inwardly along the top roof of the space, and has a flexible inner lip that is received against the beveled inner upper wall and projects radially inwardly therefrom to wipe against the outer cylindrical face of the revolving distributor to define the seal.

It is still another object of the present invention to provide an improved flexible gas seal for the revolving distributor of a blast furnace which is inexpensive to manufacture, reliable in operation, simple to install and remove, highly efficient in preventing hot blast gas from discharging into the atmosphere and adapted for installation on any type blast furnace.

The novel features which I believe to be characteristic of my invention are set forth with particularity in the appended claims. My invention itself, however, both as to its organization and method of operation, together with further objects and advantages thereof, will best be understood by reference to the following description taken in conjunction with the accompanying drawings in which:

Figure 1 is an axial cross-section view with parts in elevation of a small bell hopper assembly and revolving distributor employing a gas seal made in accordance with the present invention;

Figure 2 is an enlarged fragmentary view similar to Figure 1 showing an alternative construction of the mechanism of Figure 1; and,

Figure 3 is an enlarged cross-sectional view of the flexible gas seal and adjacent portions of the structure of Figure 1.

There is shown generally at 10, Figures 1-3, a flexible gas seal for the revolving distributor of a blast furnace made in accordance with the present invention. The flexible gas seal 10 includes three elements, namely, segmented support seal ring 12, segmented cap ring 14 and sealing ring 16, all of which will be discussed in more detail hereinafter. The seal 10 is located near the junction of rotating bell hopper 18 and blast furnace 20 to prevent the escape of blast furnace gas generated in the furnace.

The blast furnace comprises furnace 20 and small bell hopper 18, which is mounted on top of the furnace. The charging materials—iron, ore, coke and limestone—are deposited in the hopper and are received on conical bell 22. This is done by the skip car (not shown) which is periodically filled and discharged. Since the skip car dumps from one side of the hopper 18, the charging materials are loaded onto the hopper in circumferentially uneven manner. The small bell 22 and its hopper 18 are

rotated before the small bell 22 is depressed to provide a more even distribution of the charge in the furnace.

Hopper 18 is rotated by electric motor 24. Shaft 26 of motor 24 has a pinion 28 which meshes with ring gear 30. As is best seen in Figure 1, ring gear 30 is affixed to flange 18a of hopper 18 by means of bolt 30a. The ring gear 30 is also equipped with annular beveled tracks 31 and 31a which receive the conical guide rollers 33 and 33a, respectively. These pairs of rollers are spaced about the tracks 31 and 31a to hold the bell hopper 18 on its vertical axis. Motor 24 is energized by suitable control means (not shown) to provide the requisite bell hopper rotation.

As is discussed above, bolt 30a secures ring gear 30 to flange 18a of bell hopper 18. The bolt 30a also passes through outer cylindrical jacket 32 of bell hopper 18 and secures that shell to ring gear 30. Flanges 34 are located between the outer jacket 32 and the main inner cylinder 36 of the hopper. The hopper portion 36 is made in the form of circular segments, preferably quadrants, secured together by the bolts 34a received in flanges 34.

The outer cylindrical jacket 32 extends below gear 30 and terminates at the seal ring 12. As shown, ring 30 is stationary and is affixed to the top of the furnace. The ring gear 30, the inner cylinder 36, the flanges 34 and the outer shell 34—all components of the bell hopper 18—move in unison as the motor 24 drives gear 30. The seal ring 12, the cap ring 14 and flexible seal 16 remain stationary parts. It will be noted that the outer cylinder 32 has a pair of circumferential outwardly extending ribs which are received in corresponding recesses 12a in seal ring 12. The outer cylindrical sleeve 32 also has an upper outwardly extending rib 32b which is of generally rectangular cross-section and has an annular upwardly facing groove 32c, Figure 3. The inwardly extending top flange 14a of the cap 14 overhangs rib 32b, as shown, and has a depending skirt 14b that extends into the groove 32c as shown.

The brackets 13, Figure 1, each receive an angle bar unit 15 having a horizontal part 15b, a radial vertical gusset plate 15a, and a vertical outer support plate 15c. The latter carries the trunnions 17a and 17b which support the guide rollers 19 of their vertical axes and in engagement with the outer cylindrical faces straddling the gear teeth of gear 30.

In the construction of Figure 2, the small bell hopper 136 defines the circumferential flanges or ridges 136a, as shown. The seal ring 12—of the same construction as that of Figures 1 and 3—is received over these ridges as shown, with the mating circumferential slots 12a of the seal ring each receiving one of the ridges 136a. In the construction shown in Figure 2, the bell hopper 136 has no annular ridge corresponding to ridge 32b, Figures 1 and 3, although such ridge may be provided, if desired. For this reason, the annular cap 114 which seats on the seal ring 12 as shown has a simple inwardly facing circumferential groove 114a, into which a conventional packing (not shown) may be inserted if desired. The ring 113 is sandwiched between the rings 112 and 114 to define the cavity into which the flexible seal ring 16 is disposed as hereinafter described in detail.

The construction of the flexible seal and the directly associated parts of the mechanism is shown in Figure 3. The rigid stationary seal ring 12 has an annular recess at its upper inner edge, defining the annular horizontal surface 42 and the cylindrical vertical surface 44. The fixed cap ring 14 has an annular horizontal portion 14f that overlays this recess and at its inner edge terminates in a beveled downwardly conical face 13. The conical face 13 is defined by a depending skirt terminating at the inner cylindrical face 14e which is slightly spaced from the cylindrical jacket 32. It will be noted that by this construction, there is defined an annular chamber 15 about the jacket 32 which faces the cylindrical face of the jacket

and has a downwardly extending beveled roof 13 at its inner edge.

The cap ring 14 additionally defines an upper annular chamber 17, Figure 3. The lower part of this chamber is defined by the portion 14d of the ring 14 which is downwardly beveled and terminates in the cylindrical face 14e closely adjacent the jacket 32. The top part of the upper chamber 17 is defined by the overhanging portion 14a of the cap ring 14 and the portion 32b of the jacket 32 which seats beneath this overhanging portion.

The lower annular chamber 15 receives the flexible seal ring 16. As shown, this ring at its outer periphery is received snugly in the outer portion of the chamber 15, which in this region is of rectangular cross-section as shown in Figure 3. The seal ring 16 at its upper portion extends inwardly in an overhanging portion 16b which seats against the roof 14f and terminates in the sloping downwardly extending skirt 16c. The latter at its upper beveled face seats against the downwardly beveled portion 13 of the ring 14 and extends radially inwardly of the ring 14 to mate with and seat against the outer cylindrical face of the jacket 32 as shown. The skirt 16c has a toroidal shoulder 16d on its lower outer portion which receives the spiral spring 21. The latter extends fully about the jacket 32 and is located below the lower margin of the cap 14. The spring 21 is under hoop tension and urges the unsupported extending portion of the ring 16 inwardly against the face of the jacket 32 to define an effective seal.

Preferably the seal ring 12 has a shallow annular recess 43 which serves to provide an adequate clearance between the lowermost margin of the skirt 16c of the ring 16 and the lower face of the chamber 15. This assures that the blast furnace gas pressure in the cylindrical clearance space 33 between jacket 32 and seal ring 12 is effective in the chamber 15. This gas pressure serves to reinforce the action of the spring 21 in urging the skirt 16c snugly against the cylindrical outer face of jacket 32. This is due to the unbalanced pressure against the inside face of the depending or skirt portion of the seal 16 which, it will be noted, tends to flex the ring 16 in the same manner as the spring 21.

The chamber 17 is preferably filled with grease or lubricant under modest pressure. Suitable pressure lubricant fittings (not shown) are provided at openings 17a (which are distributed about the periphery of the ring 14) to supply this grease under pressure. The pressure in this chamber, however, is definitely less than that in the clearance space 33.

In the alternative form of the structure, shown in Figure 2, the ring 113 is recessed at its upper inside edge in the same manner as the seal ring 12, Figure 3. The cap ring 114 of Figure 2 is likewise formed on its lower inner face to define a flat annular roof and a depending inner skirt in the same fashion as the top cap 14 of Figure 3. Thus the annular chamber 15 is defined in the structure of Figure 2 with the same shape as the chamber 15, Figure 3. The seal ring 16 is like ring 16, Figure 3, and is placed in chamber 15, Figure 2, and operates in the same fashion as the ring 16 of Figure 3.

Since the seal ring 16 is in thermal contact with the upper part of the blast furnace, it must withstand the heat of that portion of the blast furnace. Moreover, the ring must retain its effective sealing properties at these temperatures, including the resilience and resistance to deformation. It has been found that silicone resins are suitable for this purpose and, when molded to the form shown, are capable of withstanding temperatures as high as 500° F. without loss of their desirable characteristics of resilience, resistance to wear, and sealing ability. One such material is "Sirvane" 19913, manufactured by Chicago Rawhide Manufacturing Company. The spring 21 is preferably of stainless steel to assure that it will effectively withstand the elevated temperatures and corrosive atmosphere to which it is exposed.

The revolving distributor seal of the present invention is assembled by independently supporting the bell hopper in desired position (e.g. by suspending the same by block and tackle). At this time, or previously, the flexible seal ring 16 is placed around the cylindrical surface it encompasses (32, Figure 1 and 3, 136, Figure 2). The spring 21 is then wrapped about the portion 16c of the ring and seated in the groove 16d. The segments forming the seal ring 12 are now placed in position and anchored by the bolts 38. At this time the seal ring 16 is pushed down into the annular chamber 15, which is open at its top since the cap ring 14 is not yet in position. The segments of the cap ring 14 are now placed in position and secured in proper location by the bolts 40, Figure 3, to complete the assembly.

In the structure of Figure 2, the segments defining ring 113 are placed in position immediately after the ring 12 is assembled.

As above noted, the small bell hopper is given successive rotations in a predetermined program to distribute the load uniformly. In a typical program of this kind, there are six "rounds": (1) without rotation, (2) with 60 degrees clockwise rotation, (3) with 120 degrees clockwise rotation, (4) with 180 degrees clockwise rotation, (5) with 120 degrees counterclockwise rotation, and (6) with 60 degrees counterclockwise rotation.

In addition to the advantages set forth above, the apparatus of the present invention has been found to require less driving power than the prior units. This not only reduces the required motor size, but in addition indicates that less wear is taking place with the incident prospect of greater life.

While I have shown and described particular embodiments of the present invention, it will be understood that various modifications and alternative constructions may be made without departing from the true spirit and scope of the invention. For example, the invention may be applied to furnaces with any number of bells and bell hoppers and any one of the bell hoppers may be provided with a rotating mechanism to provide the rotating distributor action. Also the specific dimensions and configurations of the parts may be altered without changing the basic operation of the apparatus. It will be accordingly understood that I intend by the appended claims to cover all modifications and alternative constructions falling within their true spirit and scope.

What I claim as new and desire to secure by Letters Patent of the United States is:

1. A flexible gas seal construction for the revolving distributor of a blast furnace having a rotating bell hopper defining an outer cylindrical face, comprising in combination: a fixed support ring affixed to the blast furnace in the region of the juncture of the blast furnace and the bell hopper and extending around said hopper; a segmented ring mounted on said support ring and extending around said hopper, said rings coacting to define an annular chamber facing the hopper wall and having a generally rectangular cross section with a downwardly beveled inner roof surface; a sealing ring having an outer portion seated snugly in the outer portion of the chamber, an inwardly extending support portion seated against the roof of the chamber and a depending flexible lip portion seated against the beveled inner roof surface and extending inwardly of the same to bear against the hopper; and a spring encircling the flexible lip below the lower margin of the ceiling of said chamber to urge the flexible lip against the bell hopper at all times.

2. A gas seal construction for the revolving distributor of a blast furnace having a bell hopper which is rotated intermittently to distribute the charge therefrom, comprising in combination: a cylindrical outer jacket affixed to and surrounding the bell hopper, the jacket having at least one outwardly extending circumferential rib; a first segmented ring encircling the outer jacket and having a circumferential inner recess in mating relationship with

the rib of the outer jacket, the segmented ring further having an upper inner circumferential recess; a second segmented ring received over and affixed to the first segmented ring, said second segmented ring extending inwardly over said recess towards the surface of the jacket and forming a downwardly extending lip with an outer downwardly conical face terminating short of the lower edge of said recess, thus defining an annular chamber in conjunction with the first segmented ring; a flexible sealing ring received in the chamber defined by said rings, said sealing ring fitting snugly in the outer portion of said chamber and having an inwardly extending portion located at the roof thereof and extending downwardly and inwardly along the conical face of said second segmented ring and outboard the lower lip thereof to partially unsupported engagement with the face of the cylindrical outer jacket; and a spring encircling the face of the sealing ring in the region below the lower lip of said second segmented ring to flex the same inwardly against the cylindrical jacket surface.

3. A gas seal construction for the revolving distributor of a blast furnace having a bell hopper which is rotated intermittently to distribute the charge therefrom, comprising in combination: a cylindrical outer jacket affixed to and surrounding the bell hopper, the jacket having at least one outwardly extending circumferential rib; a first segmented ring encircling the outer jacket and having a circumferential inner recess in mating relationship with the rib of the outer jacket, the segmented ring further having an upper inner circumferential recess; a second segmented ring received over and affixed to the first segmented ring, said second segmented ring extending inwardly over said recess towards the surface of the jacket and forming a downwardly extending lip with an outer downwardly conical face terminating short of the lower edge of said recess, thus defining an annular chamber in conjunction with the first segmented ring; a flexible silicone resin ring received in the chamber defined by said rings, said sealing ring fitting snugly in the outer portion of said chamber and having an inwardly extending portion located at the roof thereof and extending downwardly and inwardly along the conical face of said second segmented ring and outboard the lower lip thereof to partially unsupported engagement with the face of the cylindrical outer jacket; and a spring encircling the face of the sealing ring in the region below the lower lip of said second segmented ring to flex the same inwardly against the cylindrical jacket surface.

4. A gas seal construction for the revolving distributor of a blast furnace having a bell hopper defining a cylindrical outer face with at least one outwardly extending circumferential rib which is rotated intermittently to distribute the charge therefrom, comprising in combination: a first segmented ring encircling the outer jacket and having a circumferential inner recess in mating relationship with the rib of the bell hopper, the segmented ring further having an upper inner circumferential recess; a second segmented ring received over and affixed to the first segmented ring, said second segmented ring extending inwardly over said recess towards the surface of the jacket and forming a downwardly extending lip with an outer downwardly conical face terminating short of the lower edge of said recess, thus defining an annular chamber in conjunction with the first segmented ring; a flexible sealing ring received in the chamber defined by said rings, said sealing ring fitting snugly in the outer portion of said chamber and having an inwardly extending portion located at the roof thereof and extending downwardly and inwardly along the conical face of said second segmented ring and outboard the lower lip thereof to partially unsupported engagement with the face of the cylindrical face of the hopper; and a spring encircling the face of the sealing ring in the region below the lower lip of said second segmented ring to flex the same inwardly against the cylindrical hopper surface.

5. A gas seal construction for the revolving distributor of a blast furnace having a bell hopper defining a cylindrical outer face with at least one outwardly extending circumferential rib which is rotated intermittently to distribute the charge therefrom, comprising in combination: a first segmented ring encircling the outer jacket and having a circumferential inner recess in mating relationship with the rib of the bell hopper, the segmented ring further having an upper inner circumferential recess; a second segmented ring received over and affixed to the first segmented ring, said second segmented ring extending inwardly over said recess towards the surface of the jacket and forming a downwardly extending lip with an outer downwardly conical face terminating short of the lower edge of said recess, thus defining an annular chamber in conjunction with the first segmented ring; a flexible silicone resin sealing ring received in the chamber defined by said rings, said sealing ring fitting snugly in the outer portion of said chamber and having an inwardly extending portion located at the roof thereof and extending downwardly and inwardly along the conical face of said second segmented ring and outboard the lower lip thereof to partially unsupported engagement with the face of the cylindrical face of the hopper; and a spring encircling the face of the sealing ring in the region below the lower lip of said second segmented ring to flex the same inwardly against the cylindrical hopper surface.

6. In a sealing unit for the revolving cylindrical distributor hopper of a blast furnace, the improvement comprising: a fixed means defining an annular chamber having a floor and a roof and encircling and facing the cylindrical face of the hopper and in communication at its floor with the interior of the blast furnace, the roof having a downwardly beveled inner portion terminating close to but in spaced relation to the hopper and above the floor; an annular flexible seal located in said chamber, said seal being snugly received in the chamber at its outer periphery and having a depending conical skirt

portion extending along the beveled inner portion of the roof of the chamber and inwardly thereof to wipe against the face of the hopper; and spring means girdling the outer face of said skirt below the lower edge of the roof of the chamber to flex the lip of the seal inwardly against the cylindrical distributor surface.

7. In a sealing unit for the revolving cylindrical distributor hopper of a blast furnace, the improvement comprising: a fixed means defining an annular chamber having a floor and a roof and encircling and facing the cylindrical face of the hopper, and in communication at its floor with the interior of the blast furnace, the roof having a downwardly beveled inner portion terminating close to but in spaced relation to the hopper and above the floor; an annular flexible silicone resin seal located in said chamber, said seal being snugly received in the chamber at its outer periphery and having a depending conical skirt portion extending along the beveled inner portion of the roof of the chamber and inwardly thereof to wipe against the face of the hopper; and spring means girdling the outer face of said skirt below the lower edge of the roof of the chamber to flex the lip of the seal inwardly against the cylindrical distributor surface.

8. In a sealing unit for the revolving distributor hopper of a blast furnace, the improvement comprising: means defining a conical support surface adjacent to but spaced from the hopper; an annular flexible silicon resin seal ring having a conical web seated at its inner surface on said support surface and extending to wiping contact with the hopper; and, spring means girdling the seal ring on a circle of the contact located between the lip of the support surface and the line of contact with the hopper to flex the seal ring against the hopper.
